Primary Examiner — Austin Murphy

(57) **CLAIM**

The ornamental design for a hand strap, as shown and described.

DESCRIPTION

FIG. 1 is a perspective view of a hand strap showing the claimed design;
FIG. 2 is a front elevational view thereof;
FIG. 3 is a rear elevational view of thereof;
FIG. 4 is a left side elevational view of thereof;
FIG. 5 is a right side elevational view of thereof;
FIG. 6 is a top plan view of thereof;
FIG. 7 is a bottom plan view of thereof;
FIG. 8 is a cross-sectional view along line A-A of FIG. 2; and,
FIG. 9 is another perspective view showing the hand strap for use with a portable electronic device.
The broken lines are directed to environment and are for illustrative purpose only; the broken lines form no part of the claimed design.
